UNITED STATES PATENT OFFICE.

ELDRED G. HAY, OF LYNDHURST, SOUTH CAROLINA.

MAILING-TUBE.

1,032,282.

Specification of Letters Patent Patented July 9, 1912.

Application filed June 22, 1911. Serial No. 634,740.

To all whom it may concern:

Be it known that I, ELDRED G. HAY, a citizen of the United States, residing at Lyndhurst, in the county of Barnwell and State 5 of South Carolina, have invented certain new and useful Improvements in Mailing-Tubes; and I do hereby declare the following to be a full, clear, and exact description of the invention, such as will enable others 10 skilled in the art to which it appertains to make and use the same.

This invention relates to improvements in mailing tubes, and the primary object of the invention is to provide a mailing tube suitable 15 for containing various articles and the address which is detachably connected to the tube so that it may be used as a return tube without necessitating the pasting of a wrapper thereon or placing the address on the 20 tube itself.

The invention is particularly adaptable for use in connection with such articles as 25 films or photographic prints which are mailed by customers to a photographic supply house for development and finishing, and are returned again to the customer in their finished condition.

With this object in view, the invention consists in the arrangement and combination 30 of parts hereinafter described, and while the invention is not restricted to the exact details shown and described, still for the purpose of disclosure reference is had to the accompanying drawing illustrating the 35 same, and in which drawing like characters designate the same parts in the several views, and in which—

Figure 1 is a view in elevation showing 40 the mailing tube with the address slip attached thereto and sealed. Fig. 2 is a similar view showing the address slip partially attached to the mailing tube. Fig. 3 is a longitudinal sectional view. Fig. 4 is an 45 end view looking at the detachable cap for the tube and showing the address slip sealed thereto. Fig. 5 is a cross section through the tube, and Fig. 6 is an end view of the tube opposite to that shown in Fig. 4.

In practice the tube is made of any suitable 50 material, but generally is made of the usual paste board material, and from Figs. 2 to 5 it will be seen that the tube is built up of two layers, the inner layer 1 being in the form of a cylindrical tube and may be in-

tegrally joined, but is preferably separated 55 as at 2, the object being that the tube can be readily formed by bending.

Substantially encircling this inner tube 1 is an outer tube section 3, the ends of which may be spaced apart about one-half of an 60 inch, as at 4, leaving a recess 5, over which is pasted a suitable strip of transparent material 6, and this transparent material may be of such strength as to hold the outer tube 65 layer 3 in position on the inner tube, or the tube 3 may itself be affixed by glue, or otherwise, to the inner tube.

Preferably both ends of the tube are closed, one by a removable cap hereinafter referred to, and the end opposite to the removable cap may be provided with a corrugated reinforcement 7 of paste board or metal, and, indeed, this end of the tube may be provided with a detachable cover, the same as the other end, which has a metal 75 threaded rim, over which is threaded the closing cap 8. This closing cap 8 is provided with a slot 9 (Fig. 4) adapted to register with the recess 5, forming with the transparent portion 6 a pocket for the reception of an address slip 10 of a length slightly in excess of the length of the pocket to form a tab 11, adapted to be pasted over the top of the cap 8 and hold the address slip in place, while at the same time sealing 80 the package.

It will be obvious that in operation the contents of the package are inserted and the metal cap 8 screwed in position, whereupon the address slip is inserted and the tab 11 90 pasted to the top. Before inserting the address slip, if it is desired, the sender may place his own address inside of the pocket, or the same may be printed on the tube 2 itself, within the recess 5, and will act as a 95 return address to insure the return of the tube with its contents in due course to the sender.

Having thus described a practical and preferred embodiment of the invention, the 100 particular features of novelty will now be pointed out more succinctly in the following claim:—

In a mailing tube the combination of an inner tubular member; an outer member 105 closely overlying said inner member and having the edges thereof separated to provide a recess; a transparent strip overlying

said recess and forming a closed pocket; an address slip adapted to be inserted in said pocket; a cap closing one end of the tube; and a removable second cap closing the 5 other end of the tube, said second cap provided with a slot adapted to register with the open end of said pocket, and said slip having a projecting portion adapted to be

sealed against the outer face of the removable cap, substantially as described.

10

In testimony whereof, I affix my signature, in presence of two witnesses.

ELDRED G. HAY.
